Inventor
A. G. Bagg, by his attorney
J. Johnston.

United States Patent Office.

ALBERT G. BAGG, OF HOLLAND PATENT, NEW YORK.

Letters Patent No. 99,132, dated January 25, 1870.

IMPROVEMENT IN CHEESE-PRESSES.

The Schedule referred to in these Letters Patent and making part of the same.

To all whom it may concern:

Be it known that I, ALBERT G. BAGG, of Holland Patent, in the county of Oneida, and State of New York, have invented a new and useful Improvement in "Cheese-Press;" and I do hereby declare that the following is a full, clear, and exact description thereof, reference being had to the accompanying drawings, and to the letters and figures of reference marked thereon—

The nature of my invention consists in providing a cheese-press with an adjustable weight, combined with a table, supported on springs, said weight, table, and springs so acting with relation to each other, that a pliant pressure is brought to bear on the cheese, as hereinafter described.

To enable others skilled in the art to make and use my invention, I will proceed to describe its construction and operation.

In the accompanying drawings, which form part of my specification.

Figure 1 is a front elevation of my improvement in cheese-press, and represents a portion of the bottom cross-timber broken away, for the purpose of showing the relation of the springs to the table.

Figure 2 is an end elevation of the press.

In the accompanying drawings—

A A' B C represent the frame of the press.

On the inside of the timbers A and A' are grooves, into which are fitted the guides e and f, of the weight-box D, which is provided with a cross-bar, E, in which is pivoted a pulley, 1.

The upper side of the weight-box is left open, for the purpose of readily placing weights in it, and for removing weights from it. The weights to be placed in the weight-box D may be stones or pieces of metal, or the weights may consist of a series of square metallic blocks, of any desired size.

In the upper cross-timber B are pivoted pulleys 2 and 3, and to the under side of the timber is secured a staple, R, to which is attached a rope, 4, which passes down and under pulley 1, and then up and over pulleys 2 and 3, and then down to shaft y, to which it is secured.

On one end of the shaft y is a wheel, h, which gears into a small wheel, i, on the end of shaft w, which is provided with a crank, J.

The shafts w and y are secured in position on the frame-timber A' by means of the bearings 7 and 8.

The cogs or teeth on the periphery of the wheels h and i should extend around the whole circumference of the wheels, as indicated by red lines 6.

To the timber A' is pivoted a ratchet, the hooked point of which drops into the spaces between the teeth of the wheel h.

In the cross-timber C are made four cavities or chambers, in the bottom of which are placed India-rubber springs x, on which rests the standard S, of the table P, on which is placed a press-board, o, in which is made a groove or channel, u, for carrying off the whey or serous matter, pressed out of the cheese-curd.

The press-board o is provided with a pin, 5, for holding in place a disk, n, the diameter of which is nearly the same as the inside diameter of the "cheese-hoop," m, which is provided with a follower, l, which is adapted in diameter to the inside diameter of the "cheese-hoop" m.

Other forms and kinds of springs, and a different arrangement of them, may be used as a substitute for the gum springs x, and used in combination with the table P, and the pressing-device, hereinbefore described.

As the construction and arrangement of the several parts of my improved cheese-press, and the relation they bear to each other, will be readily understood from the foregoing description, and by reference to the accompanying drawings, I will therefore proceed to describe the operation of my invention.

Having all things constructed and arranged as hereinbefore described, and the desired weight placed in the weight-box D, the ratchet K is unshipped, the box D is raised up by turning the crank J, which will cause the wheel i to revolve the wheel h and shaft y, which winds on it the rope 4, and thereby draw upward the weight-box D, which is held in the desired position by the ratchet K.

The cheese-hoop is then arranged in position on the press-board o, which rests on the table P, and is provided with the pressing-cloths, after which the "cheese-hoop" m is then filled with the cheese-curd, after which the curd is properly covered with a cloth. The follower l is then set on top of the curd, as indicated in fig. 1.

The ratchet K is then unshipped, and weight-box D lowered, so that its weight will come down on the follower l, and thereby press the curd in the "cheese-hoop" m, and thereby press out of it the whey or serous matter, which may be in it.

The advantage of my improvement in cheese-press consists in combining the flexible action of springs with weights, and thereby bringing a pliant pressure upon the cheese-curd, which will equalize the pressure on all parts of the curd, and thereby cause uniform solidity of the cheese.

The facility afforded by the arrangement of the weight-box D, and the means for manipulating it, and the weight in it, will be very apparent to the manufacturer of cheese.

Having thus described the nature, construction, and operation of my improvement,

What I claim as of my invention, is—

1. The combination and arrangement of the springs x, weight-box D, and table P, constructed and operating substantially as herein described, and for the purpose set forth.

2. The arrangement of the weight-box D, pulleys 1, 2, 3, rope 4, wheels h and i, ratchet K, table P, and press-board o, constructed, arranged, and operating as herein described.

Witnesses:

ALBERT G. BAGG.

JOHN G. COTES,
HULBERT POWELL.
